UNITED STATES PATENT OFFICE

FREDERICK GUS FAUST, OF COLUMBIA, MISSOURI

SAFETY RAZOR

Application filed October 14, 1930. Serial No. 488,665.

This invention relates generally to safety razors and particularly to a new and novel safety razor of the stropable type, and which is adapted to be honed with the same motion and mechanical movements by which it is stropped, and which embodies the features of novelty and advantage which will be very clearly perceived in the following description thereof.

10 It is an object of this invention to provide a strong and rugged safety razor which will last a long time in service, being simple and effective in operation, and which may be cheaply manufactured, and readily accessible 15 for repair and replacement of parts.

These and other objects of the invention, its nature and its composition and arrangement and combination of parts will be readily understood by any one acquainted with the 20 art to which this invention relates upon consulting the following descriptions of the drawings, in which:—

Figure 1 is a general side elevational view 25 of my improved safety razor taken from the side on which is mounted the chief actuating mechanism.

Figure 2 is a side elevational view taken from the other side of the safety razor.

Figure 3 is a top view thereof.

30 Figure 4 is a detailed enlarged perspective view of the rocker.

Figures 5 and 6 are views illustrating the method of stropping the razor employing a strop.

35 Referring in detail to the drawings the numeral 5 designates generally the razor frame which is of flat, generally U-shaped form, the outer ends of the legs of the U being forwardly and downwardly beveled as

40 at 6 and rounded as at 7 to merge with the beveled portion 6. On the lower edge of each leg 8 of the main razor frame 5 and near the outer end thereof adjacent the curved portion 7 is a downward projection 9 which is

45 adapted to be passed on each side of the strop, so as to keep the razor squarely upon the strop during the stropping operation. A handle of suitable form is fastened to the middle of the bight portion of the main razor frame and it is projected in the same longi-

tudinal plane and rearwardly from the bight portion as indicated by the numeral 10. Between the outer lower end portions 7 of the legs 8 is fixed a bar which is adapted to prevent the strop from coming into frictional contact with a shaft 11 journaled across the legs of the main frame 5 and concentrically with the curved portion 7, which has a cog wheel 12 mounted on what shall be hereafter called the "right side" of the razor, and mounted on this shaft 11 and fixed for rotation therewith is a razor carrying frame made up as follows.

A thin metal plate 13 has one longitudinal edge bent over and about the shaft 11 and closely compressed thereagainst, and another plate corresponding to the plane portion of the plate 13, as indicated by the numeral 14 is hinged to one edge of the plate 13, so as to swing in the direction of its length, to embrace a blade 15 which is placed directly upon the plate 13, and the other end of the plate 14 engages with a two part friction latch 16. The hinged connection of the plates 13 and 14 is generally designated 17 in Figure 3. To prevent undue backward motion of the blade a tongue 18 is struck up from the rear edge of the plane portion of the plate 13 and it is erected to pass through a slot 19 in the rear edge of the plate 14, and hooked thereover. The blade is struck out adjacent the hinge portion 17 and the latch 16 so as to engage therebehind to prevent coming forward out of position. On the left side of the main razor frame 5 there

85 rises from the rear end portion of the contiguous leg thereof a projection 20, the upper end of which is adapted to frictionally engage a lug 21 which projects from the contiguous side of a swingable guard which comprises a pair of journaled triangular end pieces 22, a smooth curved cross bar 23 and a cross member parallelly spaced from the cross bar, on which centrally thereof projects a finger piece 24 for rocking the guard structure on a pin 25 which is journaled across the upper rear portion of the leg 8 of the main frame 5, so that the guard structure generally designated 22 has its outer ends 95 within the legs, and is pivoted so as to meet 100

the edge of the razor in the outer ends thereof with a pair of hooks 26 which form guards for the sharp corners thereof and retain the razor edge in spaced relation with the transversely curved guard 23, when the razor blade 15 is in the shaving position. The guard structure generally designated 22 is adapted to be drawn back during the stropping operation as shown in Figures 5 and 6, and the projection 20 locks in front of the lug 21, to prevent accidental return motion of the guard structure, which might interfere with the stropping operation.

The stropping rocker is generally designated by the numeral 27. It comprises a pair of generally triangular ends 28 in the small ends of which there is an aperture 29 to receive the ends of a shaft 30 which is journaled across and between the rear lower portion of the leg 8. Opposite the aperture 29 there is secured to the edges of the triangular sides 28 and at the edge thereof and in right angular relation therewith, a flat bar 31 which has a convex concave cross section, the 25 convexity being disposed on the far side from the point of contact with the sides 28 as shown in Figure 4. Projecting horizontally and in the plane of the sides 28 is a projection in the general form of a numeral 7 designated by the reference numeral 32. On the top of the 7 there is a segment of gear teeth 33. The relation of parts and proportion is such that the teeth 33 will be normally engaged in mesh with the teeth of the cog 30 wheel 12.

The method of stropping the razor is shown in Figures 5 and 6, and the action of the rocker 27. Referring to Figure 5 it will be seen that the rocker 27 is reacting to a 40 motion along a strop in the direction toward the operator thereof, in which the razor blade is projected away from the operator by the action of the rocker. Referring to Figure 6 the position of the parts and the 45 razor blade is shown in the complementary stroke, and away from the operator thereof so that the blade and its companion structure is passed completely through a semi-circular rotation to engage the opposite edge with the 50 strop.

For holding the razor on a stone or the like, the element seen in detail in Figure 4 is employed instead of that form seen in the other figures. The only difference in this 55 rocker is the provision that the segmental gear piece 33a is placed exactly opposite the teeth 33. In this formation it is required that the end portion of the 7-formation 32 be cut out as in 34 to provide the oppositely 60 faced gear teeth 33a.

This razor may be sharpened on either a flexible strop of leather or canvas, or on any kind of an edge producing material or structure in either a vertical or a horizontal position, the arrangement being such that the 65

friction is not placed upon the razor carrying structure, but upon rocker element 27. The smooth guard of transverse curved formation provides a much smoother shave than obtainable with a toothed guard. The defects incident to the structure of razor which employs a strop threaded through a series of engaging rollers or the like are eliminated in the invention. The spaced relation of the cutting edge of the blade and the guard permits plenty of room between the guard and blade to allow lather and beard hairs to pass therebetween. The stropping and the shaving operation may be performed with one hand.

It is to be definitely understood that I do not desire to limit the application of this invention to the particular modification set out herein to illustrate the same, and any change or changes may be made in material and structure and arrangement of parts consistent with the spirit and scope of the invention.

Having thus described the invention, what is claimed as new is:—

1. A safety razor of the type described comprising a horizontally disposed handle, a U-shaped frame secured at its bight portion to one end of said handle, a pivoted blade holder between the outer ends of the legs of the frame, a shaft journaled through said ends and carrying said blade holder, a cog wheel on one end of the shaft outside the frame, a strop engaging rocker pivoted to the rear portion of the frame, a forward extension on the rocker carrying a segment of gear teeth for normally meshing with said cog wheel and rotating the same when the rocker is drawn over the surface of a strop, and a guard structure pivoted on the upper rear portion of the frame and adapted to receive the cutting edge of the blade and retain the same in shaving position, said guard adapted to be disengaged from the blade and position out of the sphere of motion of said blade during the stropping operation, and a dependent guide lug on the forward lower edge of each leg of the frame for confining the strop and guiding the razor squarely upon the strop during the stropping operation.

2. A safety razor of the type described comprising a horizontally disposed handle, a U-shaped frame secured at its bight portion to one end of said handle, a pivoted blade holder between the outer ends of the legs of the frame, a shaft journaled through said ends and carrying said blade holder, a cog wheel on one end of the shaft outside the frame, a strop engaging rocker pivoted to the rear portion of the frame, a forward extension on the rocker carrying a segment of gear teeth for normally meshing with said cog wheel and rotating the same when the rocker is drawn over the surface of a strop,

and a guard structure pivoted on the upper rear portion of the frame and adapted to receive the cutting edge of the blade and retain the same in shaving position, said
5 guard adapted to be disengaged from the blade and positioned out of the sphere of motion of said blade during the stropping operation, and a dependent guide lug on the forward lower edge of each leg of the frame
10 for confining the strop and guiding the razor squarely upon the strop during the stropping operation, and a projection on the upper edge of one of said legs, and a laterally projecting lug on the companion side of
15 the guard structure for cooperation with said projection for releasably locking said guard in stropping position.

In testimony whereof I affix my signature.
FREDERICK GUS FAUST.
